Inventor,

William J. Gohn
By his Atty
W. A. Ruff

UNITED STATES PATENT OFFICE.

WILLIAM JAMES GOHN, OF OAKWOOD, ILLINOIS.

CORN-CULTIVATOR.

SPECIFICATION forming part of Letters Patent No. 403,426, dated May 14, 1889.

Application filed January 24, 1889. Serial No. 297,363. (No model.)

To all whom it may concern:

Be it known that I, WILLIAM JAMES GOHN, of Oakwood, in the county of Vermilion and State of Illinois, have invented certain new and useful Improvements in Corn-Cultivators; and I do hereby declare the following to be a full, clear, and exact description of the invention, such as will enable others skilled in the art to which it appertains to make and use the same.

10 My invention relates to an improvement in cultivators, the object of the same being to provide a self-adjusting arch attachment which may be secured to any cultivator.

15 A further object is to provide an attachment of such character as will enable the operator to have control of both sides of the cultivator by the employment of either hand for the purpose of keeping the shovels at a fixed distance from each other while the 20 same are making side motions, also to enable the operator to widen or narrow the distance between the shovels, thereby enabling the same to be set so as to throw the soil toward the corn, and thereby prevent the shovels 25 from spreading.

With these ends in view my invention consists in the certain features of construction and combinations of parts, as will be herein-after fully described, and pointed out in the 30 claims.

In the accompanying drawings, Figure 1 is a front view of the device. Figs. 2 and 3 are detached views of the brace and socket. Fig. 4 is a top plan view, and Fig. 5 is a view in 35 side elevation.

The vertical rods A are parallel to each other, as shown, and are curved at the top toward each other, forming an arch. The ends

B of the rods A engage the sleeve C, and are adjustable therein by means of the bolt-holes 40 D, formed in the rods and sleeve, the same being adapted to register with each other at suitable intervals. The bolts E engage said holes D, and have secured to their lower curved ends the braces F, the lower ends of 45 which are bent and passed through the holes G in the rods A.

The lower ends of the rods A are journaled in the boxes H, the same being secured between the forked ends of each of the beams 50 I, serving as a brace therefor and enabling the side motions of the shovels without any strain being communicated to the beams I, which are pivoted to the axle K.

It will be seen that by the employment of 55 the boxes H the beams I may be adjusted relative to each other in connection with the rods A and the sleeve C without difficulty or disarrangement of the parts below the sleeve.

Having fully described my invention, what I 60 claim as new, and desire to secure by Letters Patent, is—

In a cultivator, the rods A, adjustably secured in the sleeve C, the lower ends of said rods being journaled in the boxes H, which 65 are secured to the beams I, the rods A being adjustably secured by means of the braces F, secured to said rods and the sleeve C, substantially as shown and described.

In testimony whereof I have signed this 70 specification in the presence of two subscribing witnesses.

WILLIAM JAMES GOHN.
